UNITED STATES PATENT OFFICE

173,196

HOSIERY ENVELOPE

George Gregory Gallico, Jr., Ridgewood, N. J., assignor to Chadbourn Hosiery Mills, Incorporated,
a corporation of North Carolina

Application April 9, 1954, Serial No. 29,931

Term of patent 14 years

(Cl. D58--2)

To all whom it may concern:

Be it known that I, George Gregory Gallico, Jr., a citizen of the United States of America, residing at Ridgewood, in the county of Bergen and State of New Jersey, have invented a new, original, and ornamental Design for a Hosiery Envelope, of which the following is a specification, reference being had to the accompanying drawing, forming part thereof, in which:

Fig. 1 is a front elevational view of a hosiery envelope, illustrating my new design; and

Fig. 2 is a rear elevational view thereof.

I claim:

The ornamental design for a hosiery envelope, as shown.
